[57] CLAIM

The ornamental design for a handle grip for a bicycle, as shown and described.

DESCRIPTION

FIG. 1 is a front view of a hadle grip for a bicycle showing my new design;

FIG. 2 is a rear view thereof;

FIG. 3 is a top plan view thereof;

FIG. 4 is a bottom plan view thereof;

FIG. 5 is a left side view thereof;

FIG. 6 is a right side view thereof;

FIG. 7 is a cross sectional view thereof taken along with line A—A in FIG. 6;

FIG. 8 is a perspective view thereof; and,

FIG. 9 is a referential cross-sectional view thereof showing the grip in use, the broken lines being for illustrative purposes only and form no part of the claimed design.
